(57) **CLAIM**

I claim the ornamental design for a straps connector, as shown.

DESCRIPTION

FIG. 1 is a front/right-side/top perspective view of a straps connector showing our new design;

FIG. 2 is a front-side elevational view thereof;

FIG. 3 is a rear-side elevational view thereof;

FIG. 4 is a left-side elevational view thereof;

FIG. 5 is a right-side elevational view thereof;

FIG. 6 is a top-side elevational view thereof;

FIG. 7 is a bottom-side elevational view thereof; and,

FIG. 8 is a perspective view of an electronic device illustrating the features of the straps connector of FIGS. 1-7. In FIG. 8, the inventive straps connector of FIGS. 1-7 is in solid lines, and the electronic device is in broken lines to show an example environment of the inventive straps connector of FIGS. 1-7, with the broken lines not forming a part of the claimed design.

The broken lines are provided to illustrate environmental structure that forms no part of the claimed design.
